UNITED STATES PATENT OFFICE

115,389

DESIGN FOR A SOUVENIR KEY

William R. Burke, Berkeley, Calif., assignor to California Retail Jewelers Association, Inc., San Francisco, Calif., a corporation of California

Application January 24, 1939, Serial No. 82,556

Term of patent 3½ years

To all whom it may concern:

Be it known that I, William R. Burke, a citizen of the United States of America, residing at Berkeley, in the county of Alameda and State of California, have invented a new, original, and ornamental Design for a Souvenir Key, of which the following is a specification, reference being had to the accompanying drawing, forming part thereof.

The figure is a front elevational view of a souvenir key showing my new design.

The rear face of the key is plain.

I claim:

The ornamental design for a souvenir key, as shown and described.

WILLIAM R. BURKE.
